UNITED STATES PATENT OFFICE.

ALFRED W. BRUCE, OF NEW YORK, N. Y.

LATERAL-MOTION APPLIANCE FOR LOCOMOTIVE DRIVING BOXES.

1,414,456.

Specification of Letters Patent. Patented May 2, 1922.

Application filed August 18, 1921. Serial No. 493,300.

To all whom it may concern:

Be it known that I, ALFRED W. BRUCE, a citizen of the United States, and a resident of New York, in the county and State of 5 New York, have invented a certain new and useful Improvement in Lateral-Motion Appliances for Locomotive Driving Boxes, of which improvement the following is a specification.

10 The object of my invention is to provide means for affording and controlling lateral motion in the driving boxes of locomotive engines, which shall be of simple and inexpensive construction, and of special applicability in connection with the rear driving axles of locomotives in which trailing trucks are not applied, with the result of enabling a locomotive, having a comparatively long rigid wheel base, to pass through 15 curves of comparatively short radius, without liability to derailment, and without inducing undue or excessive wear of wheel flanges and rails.

20 The improvement claimed is hereinafter 25 fully set forth.

In the accompanying drawings: Figure 1 is a view, the right hand half of which is an outer end elevation of a locomotive driving box, and an outer side elevation of its 30 pedestal, and the left hand half, a vertical transverse section through the driving box and axle, on the line *a a* of Fig. 2, illustrating an application of my invention; Fig. 2, a vertical transverse section through one in 35 the side frames, and a side view, partly in section, of one of the members of the driving box structure; Fig. 3, a partial plan view of the spring and equalizer supporting beam; Fig. 4, a view, taken similarly to 40 Fig. 1, illustrating a structural modification; Fig. 5, a vertical transverse section through the side frame of Fig. 4, and a side view of the adjoining member of the driving box structure; Fig. 6, a half plan or top 45 view; and, Fig. 7, a vertical transverse section through one of the side frames, and a longitudinal section through the adjoining member of the driving box structure, on the line *b b* of Fig. 4.

50 My invention is herein exemplified as applied in connection with a locomotive engine, the frame of which is of the standard

"bar" type, and comprises two side members, which are, as in present practice, spaced at the maximum distance apart available under the necessary limitation imposed by the width between driving wheel hubs. 55 Each of the side frame members comprises, so far as the portion thereof in which the driving axles are fitted, is concerned, the usual top rail, 1, bottom rail, 2, and connecting vertical pedestals, each of which consists of a pair of pedestal jaws, 3, in which one of the sections of a driving box structure, hereinafter described, is fitted, 60 between a wedge and a shoe, in the ordinary manner. The open space between the sections of the lower frame rail, at the bottom of the pedestal, is spanned by a pedestal tie, 5, secured removably in position by bolts. 65

In the practice of my invention, referring descriptively to the specific embodiment thereof which is herein exemplified, I provide a continuous driving box structure which accords, in all substantial particulars, 70 with that set forth in Letters Patent of the United States No. 1,057,220, granted and issued March 25, 1913, to Francis J. Cole. Said driving box structure is not, therefore, in and of itself, claimed as of my invention and need only be sufficiently herein described to make clear its function of directly applying to the driving axle, 8, the portion of the weight of the locomotive 75 which is carried upon said axle.

Two open bottom sections, each of which has an integral driving box, 4, of substantially ordinary construction, formed on its outer end, abut, and are secured together, at their inner ends, by bolts, 4^a, passing 80 through end flanges, 4^b, on the sections, and nuts, thereby constituting the continuous driving box structure above referred to. The proper longitudinal relation of the sections may be adjusted by interposed shims 85 or liners, as desired. A journal bearing, 4^c, fitting on, and corresponding in length with, one of the driving axle journals, is fitted in each of the driving boxes, and a lubricant cellar, 4^d, is fitted in each of the driving box sections, below the axle journal, and is held removably in position by bolts, in 90 the usual manner. The usual flange clearance is provided in the driving boxes, al-

lowing a lateral movement of approximately one inch in either direction.

The weight carried on the continuous driving box structure, is transmitted thereto through springs, bearing on the side frame members, and connected to equalizers, 13, which bear centrally on seats, 10^a, at the ends of a rigid yoke or spring and equalizer supporting beam, 10, extending transversely 10 on the locomotive, between the driving box structure, and the upper rails of the side frame members, and adapted to move vertically, but not laterally, relatively to the latter.

15 As shown in Figs. 1 to 3 inclusive, the supporting beam extends into the spaces between the pedestal legs, 3, and, in such case, the upper surfaces of the top rails, 1, of the side frames, are elevated above the level of 20 said rails, between the pedestals, as most clearly shown in Fig. 1. In applications to existing locomotives, the supporting beam may not be extended between the pedestal legs, and elevation of the top rails will not 25 be necessary, as indicated in Fig. 4.

The ends of the supporting beam, 10, are supported upon the driving boxes, through the intermediation of vibratable rockers, 11, which are of the three point suspension type, 30 and, in the instance shown, normally bear at two points on the driving box structure, and at one point on the supporting beam. A reverse disposition of the bearing points of the rockers, would manifestly have the 35 same operative effect, and would constitute the mechanical equivalent of that illustrated in the drawings. The rockers, 11, are set in lateral pockets, 4^a, formed integral with the driving boxes, 4, and bear on recessed seats, 40 4^b, therein, and the supporting beam, 10, bears, in turn, on the rockers, through lateral pockets, 10^b, the lower surfaces of which are oppositely inclined. The end walls, 10^c, of the pockets 10^b, form stops, which fit, with 45 easy working clearance, against the inner sides of the upper frame rails, and thereby prevent lateral movement of the beam, 10, without interfering with its vertical movements.

50 The ends of the equalizers, 13, are coupled to underhung springs, 15, which bear on the side frame members in the ordinary manner, and, as shown in Figs. 4 to 6 inclusive, the springs on opposite sides of the locomotive may be connected by transverse equalizers, 14, so as to compensate for unequal vertical movements on opposite sides. In 55 the instance exemplified, the transverse equalizers, 14, are connected with the side equalizers, 13, by hangers, 13^a, and with the springs, 15, by hangers, 13^b.

In the operation of a locomotive engine in which my invention is applied, when the continuous driving box structure is laterally deflected, in either direction, from its nor-

mal position, relatively to the side frame members, which deflection is effected by the resistance opposed by the contact of the outer track rail with the flange of the adjacent driving wheel upon the passage of the 70 locomotive from a tangent to a curve of the track, the accompanying lateral movement of the driving box structure, swings the rockers, 11, in direction similar to that of the movement of the driving box structure. This movement of the rockers, which acts to raise the supporting beam, 10, is resisted by the weight carried thereon, this resistance acting through the rockers, 11, and being determined by the angularity of 80 lines connecting the axes of their bearing points. The beam, 10, being prevented from moving laterally, the springs, 15, participate in its vertical movements, as the resistance stated is overcome, without disturbance of 85 their relation, laterally, to the side frame members or equalizer connections. As the resistance of the rail decreases, in the passage of the locomotive from a curve to a tangent of the track, the superimposed 90 weight on the rockers, 11, forces the driving box structure to its normal position, and the load is again carried on all three bearing points, as indicated in the drawings.

The desirability of the application of my 95 invention in connection with the rear driving axle of locomotives which are not provided with trailing trucks, will be obvious to those familiar with the operation of locomotives of such type. The disposition of 100 the supporting beam, equalizers, and springs, is such as to present the maximum of unobstructed space above them and between the driving wheels, and thereby to permit the ash pan and its accessories to be properly 105 located, without being interfered with by any members of the weight distributing and supporting mechanism.

I claim as my invention and desire to 110 secure by Letters Patent:

1. In a locomotive engine, the combination of two side frames; a continuous driving box structure, fitted, with the capacity of relative transverse movement, therein; a superposed vertically movable spring and equalizer supporting beam, which extends into the spaces between the jaws of opposite pedestals of the side frames; and vibratable rockers, interposed between, and bearing on, the driving box structure and the supporting beam. 115

2. In a locomotive engine, the combination of two side frames, the tops rails of which are raised, between pedestal jaws, above their level exterior thereto; a continuous driving box structure, fitted, with the capacity of relative transverse movement, in the pedestals of said frames; a superposed vertically movable spring and equalizer supporting beam, which extends into the spaces between the jaws of opposite pedestals of the 125 130

side frames; and vibratable rockers, interposed between, and bearing on, the driving box structure and the supporting beam.

3. In a locomotive engine, a spring and equalizer supporting beam for driving box lateral motion appliances, having equalizer seats on its top, adjoining its ends; lateral

rocker pockets on its bottom; and vertical stops, between said pockets and its ends, for the prevention of end movement.

ALFRED W. BRUCE.
